RADIO AMPLIFYING CIRCUIT

Rinaldo De Cola, Chicago, Ill., assignor to Belmont Radio Corporation, Chicago, Ill., a corporation of Illinois

Application December 13, 1940, Serial No. 370,053

6 Claims. (Cl. 250—40)

This invention relates to radio frequency circuits and more particularly to radio frequency amplifiers of the permeability tuned type.

In permeability tuned circuits of the prior art, considerable difficulty has been encountered in obtaining a uniform radio frequency response and high overall selectivity over a complete tuning range. In some instances of the prior art, a uniform response as a function of the frequency has been provided by maintaining uniform the L/R ratio of the permeability tuned coil, L/R being maintained constant by a suitable construction of the tuning core. It is apparent of course, that this constant L/R as a function of the frequency is identical to a Q variation which is directly proportional to the frequency since $WL/R = Q$, where W is the frequency. The attainment of a uniform gain in this manner, however, limits the overall selectivity of the circuit by virtue of the fact that the lowest L/R ratio occurs when the inductance of the tuning coil is at its lowest value, namely, when the tuning core is completely outside the field of the coil. Systems, therefore, using a constant L/R to effect a uniform radio frequency gain are limited to this low L/R factor throughout the tuning range of the core. Thus a well-built and designed coil for permeability tuned circuits has a Q, when the magnetic core is entirely removed from its field, of approximately 70, while its Q at one-third the frequency, which represents an average tuning range for one band of a radio receiver, is one-third of 70 or about 23. Since a coil Q of 23 represents a serious disadvantage from the standpoint of selectivity, maintaining the radio frequency response uniform by a constant L/R ratio has not been entirely satisfactory. A further difficulty in the permeability tuned circuits of this type is found in the lack of adequate image attenuation; high image attenuation being obtained only by limitations of the circuit to rather selected operating conditions.

It is an object of this invention, therefore, to provide an improved radio frequency circuit of permeability tuned type.

Another object of this invention is to provide a permeability tuned radio frequency amplifier circuit which is characterized by a substantially uniform gain over a wide frequency range.

Yet another object of this invention is to provide a permeability tuned circuit which is characterized by a high attenuation of the image frequency.

A further object of this invention is to provide a permeability tuned radio frequency amplifier

circuit which is characterized by a substantially uniform gain and a high attenuation of the image frequency over a wide frequency range.

Another object of this invention is to provide a permeability tuned radio frequency amplifier circuit which can be operated with equal efficiency to provide a substantially uniform radio frequency gain over a complete tuning range regardless of whether the antenna circuit gain or the gain at some other point of the receiver, increases or decreases with an increase in frequency.

A further object of this invention is to provide a permeability tuned circuit in which the plate circuit impedance is practically independent of the frequency and in which a high selectivity is effected over a complete tuning range.

A feature of this invention is found in the provision of a permeability tuned radio frequency amplifier circuit including parallel tuned and series resonant circuits, in which a pair of tuning coils are connected in series aiding and mutually coupled to one another in a manner such that a proper image tracking is obtained by a variation essentially only in the mutual coupling reaction between the coils.

Yet another feature of this invention is found in the provision of a permeability tuned radio frequency amplifier circuit in which two serially connected coils are concentrically arranged, but spaced from each other so that their inductance is varied uniformly and concurrently, but at different rates by the passage therethrough of a magnetic core. The resultant variation in the outer coil is utilized to obtain a substantially uniform gain with high overall selectivity, over a wide range of frequencies.

Further objects, features and advantages of this invention will become apparent from the following description when taken in connection with the accompanying drawings, in which:

Fig. 1 is a schematic circuit diagram illustrating one embodiment of the invention;

Fig. 2 is illustrated similarly to Fig. 1 and shows a modified form of the invention;

Fig. 3 also illustrated similarly to Fig. 1 shows yet another form of the invention;

Fig. 4 is a sectional view of an inductor suitable for use in the circuits of Figs. 1, 2, and 3;

Fig. 5 is a graph showing by comparison some of the operating characteristics of the circuits of Figs. 1 and 3; and

Fig. 6 is illustrated similarly to Fig. 5 and shows the operating characteristics for the circuit of Fig. 2.

The permeability tuned radio frequency amplifier system of this invention includes a coil structure in the resonant circuit which is comprised of two series connected mutually aiding coils having predetermined gain versus frequency characteristics. The coils are concentrically arranged one within the other with a magnetic core adjustable along their common axis. The outer coil of larger diameter constitutes the plate load while the succeeding or amplifier tube may be connected either to the total inductance of both coils in series or only across the outer coil. In either case, a uniform gain over an entire tuning range is simply accomplished by merely selecting a pair of coils of predetermined diameters to provide for a predetermined inductance variation of the outer coil. It is contemplated that the inner coil be of a diameter substantially equal to that of the tuning core for the coils to obtain as great a change as possible in its inductance on the adjustment of the tuning core therein. A proper selection of the relative coil sizes is, therefore, restricted to merely a proper selection of the outer coil. By virtue of this difference in the sizes of the inner and outer coils, their mutual coupling and inductance are varied on passage of the tuning core therein, to vary the response gain of the circuit in accordance with the predetermined operating curve. Since the insertion of the magnetic core within the field of the coils appreciably increases the L/R ratio of the coil structure, high selectivity over the entire tuning range is provided concurrently with a uniform radio frequency response. This uniform gain can be obtained even though the Q variation of the coils is practically opposite to that required for a uniform L/R.

With the inductance of the inner coil higher than that of the outer coil, and with the grid of the succeeding tube connected across the outer coil, a resonant series circuit is formed across the outer coil. The resonant frequency of this series circuit is dependent upon the inductance of the inner coil, the mutual coupling between the two coils, and the capacitor across the total circuit. Since the mutual coupling coefficient between the coils is a function of the core position and the relative diameters of the coils, correct image tracking over the entire tuning range of the magnetic core is obtained by a proper selection of the coil diameters, this image attenuation being obtained without appreciably affecting the uniform signal gain of the system.

With reference to Fig. 1 of the drawings, the invention is seen to include a resonant circuit having a variable inductor formed with two coils 1 and 2 which are serially aiding connected. Coils 1 and 2 are concentrically arranged with coil 2 positioned within coil 1 (Fig. 4) but separated therefrom as by spacers 7. An adjustable magnetic core 3 is axially movable within coils 1 and 2, the resonant circuit being completed by an adjustable capacitor 4 which is connected across the coils 1 and 2. A vacuum tube 5, which is preferably a high plate resistance radio frequency pentode is connected to the junction of coils 1 and 2, with the control grid of a tube 6 being connected across the total inductance of coils 1 and 2. The vacuum tube 6 may be either a radio frequency amplifier similar to tube 5, or it may be a mixer tube such as is used in superheterodyne receivers. The signal response from the usual antenna (not shown) is impressed upon the control grid of vacuum tube 5. Thus in operation the resonant circuit is tuned to the frequency of

the desired signal impressed on the control grid of the tube 5 by means of the movable magnetic core 3, the voltage developed across the coils 1 and 2 being applied to the control grid of the vacuum tube 6. By means of the adjustable capacitor 4 the resonant circuit is aligned with the other variable tuned circuits of the receiver, the adjustment preferably being made at the higher frequencies of the desired tuning range 10 of the receiver, that is, when the magnetic core 3 is completely removed from within the coils 1 and 2.

With reference to Fig. 4, it is seen that coil 2 is of substantially the same diameter as the magnetic core 3. Thus as the core 3 is brought into the field of the coils 1 and 2, the inductance of the coil 2 is changed by a greater proportion than that of coil 1 because of its closer proximity to the core 3. With the proper choice or selection of the diameters of the coils 1 and 2, the change in the circuit impedance in the plate circuit of the vacuum tube 5 can be varied in such a manner as to produce a substantially constant voltage across the grid of the tube 6, as will now be explained.

As shown in Fig. 1, the voltage applied to the tube 6 may be expressed as

$$E_A = E_g G_m W L_1 Q (1 + K \sqrt{N}) \quad (1)$$

where E_g is the impressed signal on the control grid of tube 5; G_m is the mutual conductance of the tube 5; W is the resonant frequency of the resonant circuit; Q is equal to WL_1/R in which L_1 is the total circuit inductance of coils 1 and 2, and R is the effective resistance in series with the inductance L_1 ; K is the coupling coefficient between coils 1 and 2, and N is the ratio of L_2/L_1 between the coils in which L_1 and L_2 represent the inductance of coils 1 and 2, respectively. In other words, the voltage across the grid of the tube 6 varies directly with the effective plate current change of tube 5, the reactance of coil 1 and the coil factor $Q(1 + K \sqrt{N})$.

Since the tube 5 is of the pentode type, the plate current occurring therein for practical purposes, may be considered as independent of the plate load. In instances where this independence does not exist the coils 1 and 2 may be constructed to compensate for any variations in the plate current. The electrical characteristics of the coils 1 and 2, namely, the coupling coefficient (K) between the coils, the ratio (N), and the dissipation factor Q all generally increase, with a decrease in the resonant frequency. This increase is substantially uniform and occurs as the frequency is varied by adjusting the position of the magnetic core 3 in the coils 1 and 2. With the Q , K and N of the coils 1 and 2 all tending to increase with a decrease in the resonant frequency, the voltage gain applied on the grid of tube 6 correspondingly increases with such decrease in frequency. Since the plate load of tube 5 is variable directly with the impressed signal, and mutually related with the coil factor $Q(1 + K \sqrt{N})$, the invention contemplates the variation in the reactance of coil 1 to provide for a substantially uniform voltage gain being applied on the grid control of tube 6. In other words, the reactance WL_1 of coil 1 is varied to decrease uniformly at a rate commensurate with the uniform increase in the factor $Q(1 + K \sqrt{N})$. This variation in the reactance of coil 1 is accomplished by a proper selection of the diameter and distribution of turns 70 of coil 1 relative to the diameter of coil 2.

In one application of the invention coil 2 has a diameter of .221 inch and a length of 1.375 inches and is formed with 247 turns of 7-44 S. S. E. Litz wire. Coil 1 in this instance is .562 inch in diameter and 1.575 inches long and is comprised of 47 turns of #38 S. S. E. wire, 8 turns of which are wound at 20 turns per inch, 8 turns evenly spaced over .925 inch and 31 turns close wound over a quarter of an inch. The tuning core for these coils is .198 inch in diameter and 1.375 inches long. In the practice of this invention, therefore, it is seen that the diameter of coil 2 is retained substantially equal to the diameter of the core 3. Coil 2, therefore, has a higher rate of inductance change than coil 1 with the reactance change in coil 1 being dependent entirely upon the variation in the diameter of coil 1 alone.

As previously noted, with reference to Fig. 4, coils 1 and 2 are concentrically arranged with the coil 2 positioned within the coil 1. The magnitude of the inductance in each of the coils 1 and 2 thus varies concurrently and increases uniformly as the core is moved into the windings. The rate at which the separate inductance of the coils 1 and 2 increases depends upon the size of their diameters relative to the diameter of the core 3. Thus, let it be assumed that the coil 1 is wound directly about the coil 2. The magnitude and rate of increase in the inductance of coils 1 and 2 would then be substantially the same. It is readily apparent, therefore, that the total inductance of both of the coils increases at a rate corresponding to the separate rate of inductance increase in the coils 1 and 2. The voltage applied on the grid of tube 6 would thus also be increasing and would rise uniformly as the core 3 proceeded into the coils 1 and 2. This condition is illustrated by the curve A in Fig. 5.

With the coil 1 wound on a diameter somewhat larger than that of coil 2, the inductance of coil 1 as the core 3 is passed into the coils 1 and 2 increases at a rate less than that of the coil 2. As exemplary of this condition, let it be supposed that in moving the core 3 from a position outside the coils to a position fully within the coils, that the resonant frequency of the tuned circuit is changed from a certain high frequency to a frequency of only $\frac{1}{3}$ such high frequency. The total series inductance of the coils 1 and 2 is thus increased 9 times. Let it be further supposed that the extreme positions of the core 3 effects an increase in the inductance value of coil 1 which is only three times greater than its minimum value, which minimum value occurs when the core 3 is entirely removed from the coils 1 and 2. Since the reactance of coil 1 varies directly with the resonant frequency and the inductance of coil 1, it is apparent that the reactance of the coil has remained unchanged, because the resonant frequency has diminished to $\frac{1}{3}$ of its original value. This arrangement of the coils 1 and 2 thus also provides a rising gain characteristic, as shown by curve B in Fig. 5, the reactance of coil 1 remaining constant and the rise in gain being effected by the increase in the factor $Q(1+K\sqrt{N})$. It is to be noted, however, that the slope of the gain is less than that of the previously cited case where coil 1 is wound directly about coil 2, as is clearly indicated by a comparison of the curves A and B in Fig. 5.

Now let it be assumed that the coil 1 is of such a large diameter that it is not influenced by the position of the core 3 and is entirely removed

from the field of the coil 2. Under this condition the inductance of coil 1 is constant so that its reactance decreases as the frequency decreases, the variation in the reactance now being directly variable with the frequency. As the core 3, therefore, is moved within the coils 1 and 2, the voltage gain decreases. The operating characteristics of the circuit with this selection of the coils 1 and 2 is illustrated by curve D in Fig. 5.

On a comparative study of curves A, B and D, in Fig. 5, it is obvious that to obtain a uniform signal gain the diameter of coil 1 must be selected so that the reactance of the coil 1 uniformly decreases as the frequency decreases and at a rate corresponding to the uniform increase in the value of the factor $Q(1+K\sqrt{N})$ for the coils 1 and 2. It is to be understood, of course, that the variation in the reactance of coil 1 also varies the factor $Q(1+K\sqrt{N})$ to a corresponding extent since the voltage applied across the tube 6 is the combined voltage of both of the coils 1 and 2. In other words, the variation in the reactance of coil 1 to compensate for the increase in value of the factor $Q(1+K\sqrt{N})$ includes also a consideration of the slight decrease in such value as effected by the decrease in the reactance of coil 1. Since the electrical characteristics of the coils 1 and 2 are of a known value, it is apparent that this value may be set up in equational form relative to the reactance of coil 1 so that the coil performance for a particular operating condition may be predicted. On a proper selection, therefore, of coils 1 and 2, a substantially uniform signal gain for the circuit is obtained as shown by curve C in Fig. 5.

The circuit diagram shown in Fig. 2 is substantially similar to that of Fig. 1 except that the control grid of tube 6a is connected to the junction of coils 1a and 2a. The voltage applied on the tube 6a is thus the voltage across coil 1a rather than the collective or total voltage of both coils. In analyzing this circuit the voltage across the tube 6a is seen to be:

$$E_a = E_g G_m W L_{1a} Q \frac{(1+K\sqrt{N})^2}{(1+N+2K\sqrt{N})} \quad (2)$$

wherein all of the factors are similar to those previously explained in connection with Fig. 1.

When operating the circuit of Fig. 2, using the coil sizes of Fig. 1 which produced the operating curve C in Fig. 5, there is obtained the curve A' shown in Fig. 6. The voltage gain is seen to be non-uniform and upwardly sloped toward the high frequency end of the tuning spectrum, but of a greater slope than the curve C in Fig. 5. This is due to the fact that the tying of the grid of tube 6a to the junction of coils 1a and 2a removes the voltage step-up which normally occurs therebetween. A general loss, therefore, is effected in the overall gain of the circuit of Fig. 2.

As is evidenced from Equations 1 and 2 the term

$$Q \frac{(1+K\sqrt{N})^2}{(1+N+2K\sqrt{N})}$$

of Equation 2 increases less rapidly than the term $Q(1+K\sqrt{N})$ of Equation 1 as the signal frequency decreases. Thus to obtain a uniform gain for the circuit of Fig. 2 the coil 1a is reduced in diameter so that its reactance or the factor $W L_{1a}$ diminishes less rapidly as the frequency decreases. However, to provide a circuit gain in Fig. 2 which is on the order of the gain

in Fig. 1, both coils 1a and 2a are constructed with relatively larger inductance values than the corresponding coils 1 and 2 which produced the operating curve C of Fig. 5. This increased inductance provides for a substantially high initial voltage developed by the coils 1a and 2a when the core 3a is in its retracted position, at which position the compensating reactance of the coil 1a will have its greatest value. With the characteristics of coils 1a and 2a of a known value, their performance may be predetermined so that the proper coils for effecting a uniform gain at the tube 6a are readily selected. Thus in one commercial embodiment of the system of Fig. 2 coil 1a is 1.062 inches in length with a diameter of a half an inch and comprised of 68 turns of #38 S. S. E. wire wound uniformly at 64 turns per inch. Coil 2a is 1.375 inches long with a diameter of .221 inch and formed with a progressive universal winding of uniform pitch having 325 turns of 7-44 S. S. E. Litz wire. The tuning core for these coils has a diameter of .198 inch and a length of 1.375 inches. The additional initial inductance constructed in the coils 1a and 2a does not, however, impair the uniformity of the signal response, which is graphically illustrated in Fig. 6 by the curve B'.

With coil 1a of a diameter such that it is not influenced by the position of the core 3a, and entirely removed from the field of coil 2a, there results the circuit operating characteristics shown by the curve C' in Fig. 6 which is similar to the curve D in Fig. 5, the coils operating to effect a voltage gain which decreases as the frequency decreases.

As shown in Fig. 2, the circuit from tube 5a through coil 2a and condenser 4a forms a series resonance circuit across the coil 1a, the parallel circuit being comprised of the coils 1a and 2a and tuning core 3a and the condenser 4a. The resonant frequency of this series circuit, is higher than the desired signal frequency, and is determined by coil 2a, the adjustment of the condenser 4a and the polarity and magnitude of the coupling coefficient (K) between the coils 1a and 2a. By a proper selection of the relative diameters of coils 1a and 2a, a value of K is obtained which combined with the resonance of coil 2a and capacitance 4a acts to short-circuit the plate coil 1a at image frequencies whereby to substantially reduce the image voltage applied to the tube 6a. It is to be understood, of course, that the coupling coefficient (K) varies with the position of the magnetic core 3a within the coils 1a and 2a, its value being a minimum with the core entirely removed from the windings 1a and 2a and a maximum when the core is fully within the windings. The selected coils 1a and 2a, therefore, operate to vary the value of K such that the relation between the resonant frequencies of the series and parallel circuits is substantially correct over the entire frequency spectrum.

A more clear understanding of the effects of the polarity and magnitude of the mutual inductance factor (K), between the coils 1a and 2a in providing for high image attenuation is obtainable from the equation

$$f_i = f_s \left(\frac{L_{ta}}{L_{2a}(1-K^2)} \right)^{1/2} \quad (3)$$

where f_i is the frequency of image attenuation; f_s the frequency of the desired signal, and L_{ta} the total inductance of the coils 1a and 2a, the factor (K) being of positive polarity. Let it be

assumed that the parallel tuned circuit is tunable over a broadcast spectrum which extends from 550 kc. to 1500 kc. and that the intermediate frequency is about 450 kc. Since the local oscillator operates at a higher frequency than the signal frequency the range of image response will extend from 1450 kc. to 2400 kc., the image frequency being higher in frequency than the signal frequency, by twice the intermediate frequency of the receiver. The ratio of the image frequency to the signal frequency at 550 kc. is thus 2.64 and at 1500 kc. the ratio is 1.6. It is seen, therefore, that proper image tracking occurs when the frequency of the series resonant circuit, for the above mentioned frequency range, increases at a lower rate than the corresponding frequency of the parallel tuned resonant circuit.

As is apparent from the above noted ratio figures the ratio of the image frequency to the signal frequency, or frequency ratio, increases as the signal frequency decreases. From Equation 3 it is seen that this ratio f_i/f_s is directly proportional to

$$\left(\frac{L_{ta}}{L_{2a}(1-K^2)} \right)^{1/2}$$

In one commercial embodiment of the invention, the ratio of

$$\frac{L_{ta}}{L_{2a}}$$

was found to be 1.85 with the core 3a retracted and 1.6 with the core within the coils. This inductance ratio thus decreases with a decrease in the frequency, which decrease is opposite in direction to that of the ratio of the image frequency to the signal frequency. However, since the inductance ratio varies but little over the entire frequency spectrum it may be considered as being substantially constant. Consequently only the value of the mutual coupling factor $(1-K^2)$ remains to supply the necessary variation for proper image tracking. As was explained in connection with Equations 1 and 2 relative to uniform gain the coupling coefficient K increases with increasing inductance or as the frequency decreases. This increase is in the same direction as that of the ratio of image frequency to signal frequency. Since the inductance ratio

$$\frac{L_{ta}}{L_{2a}}$$

and mutual coupling factor $(1-K^2)$ alone act to affect the frequency ratio, this latter ratio is changed only by a change in the coupling factor by virtue of the inductance ratio being substantially fixed. Proper image tracking is thus obtained by a selection of the diameters of coils 1a and 2a such that the value of (K) varies with a decrease in frequency to effect attenuation of the image voltage developed by coil 1a at a rate which is in accordance with the rate in the change of the frequency ratio.

Since the coupling coefficient (K) increases as the core 3a is extended further into the field of the coils 1a and 2a, its slope value is greatest when the ratio of the diameters of coils 1a and 2a is a maximum. With the coil 1a wound tightly about the coil 2a, the coupling coefficient therebetween changes but little with the position of the core 3a. Thus high image attenuation by utilization of the coupling coefficient between the coils 1a and 2a is obtained only when the coils are relatively spaced from each other, so that for any given increment of change in the

position of the core 3a, the relative resulting change in the coil 1a will be different from the relative change which occurs in the coil 2a. It is to be noted also that the selection of the coils 1a and 2a may be such that a reasonably satisfactory uniform gain may be produced concurrently with high image attenuation. This operation of the circuit in Fig. 2 is provided by a consideration of the mutual effects of the factors governing the variations both in uniform gain and image attenuation.

In some cases, however, it may be desirable to have a radio frequency gain response other than uniform to accommodate the character of the antenna gain or other gain characteristic of a particular receiver. To maintain uniform the overall sensitivity of the receiver the radio frequency amplifier slope, in such instances, would be opposite in direction to the slope of the antenna gain. As exemplified by curves A, B, and D in Fig. 5, and curves B' and C' in Fig. 6 for the circuits of Figs. 1 and 2, respectively, it is seen that both of the circuits are sufficiently flexible in operation to compensate for a non-uniform gain in other associated parts of the receiver, such as the antenna, regardless of whether this non-uniform gain may slope up or down as the frequency increases. However, as above fully explained, curve A of Fig. 5 and curve C' of Fig. 6 graphically show an extreme operating condition for the circuits of Figs. 1 and 2, respectively. It is contemplated, therefore, to use the circuit of Fig. 2 when the receiver sensitivity slopes downwardly, or falls off, as the frequency increases, and the circuit of Fig. 1 when the receiver sensitivity increases with an increase in the frequency. It is to be understood, however, that this preference is entirely a matter of reducing the physical size of the coil assembly illustrated in Fig. 4, since the circuits of Figs. 1 and 2 operate with equal efficiency when arranged to compensate for a particular gain characteristic.

The circuit in the modified form of the invention shown in Fig. 3 is substantially identical to that of Fig. 1, except that the connection points for the plate of tube 5 and grid of tube 6 are interchanged. That is, the plate is connected to coil 2, and the condenser 4 and the grid are connected to the coil 1. For the same size coils 1 and 2 as are used in Fig. 1, the operation of the circuit of Fig. 3 is identical in all respects to that of Fig. 1, so that the response curves in Fig. 5 also graphically illustrate the operating characteristics for Fig. 3. However, this similarity in operation occurs only when the grid input or loading effects of the tube 6 on the circuit are negligible. At the higher radio frequencies this loading effect may become somewhat appreciable, and the circuit of Fig. 3, by virtue of the tube 6 being connected directly to the coil 1 acts to reduce these effects so that substantially the entire response across coil 1 is applied on the tube 6.

The invention thus provides a permeability tuned radio frequency amplifier circuit which is flexible in operation and readily adapted for application to a plurality of receiving conditions. The tuning coils of the tuning inductor are so arranged that the coupling effect therebetween is utilized to provide a high attenuation of the image frequency and a uniform gain at signal frequencies, while maintaining a high selectivity.

It is to be understood that only preferred embodiments of the present invention have been

illustrated and described herein and that modifications and alterations may be made in these embodiments which are within the full intended scope of the invention as defined by the appended claims.

I claim:

1. In a tuning system having a capacitive element and a vacuum tube with a control grid, the combination of a pair of inductive elements substantially equal in length connected with said capacitive element to form a parallel resonant circuit, said grid being connected in said circuit so as to have the total voltage developed across said inductive elements applied thereon, said inductive elements being serially aiding connected and concentrically arranged, means for mounting said inductive elements in fixed position with one entirely within the other but spaced from each other radially, a series resonant circuit including said capacitive element and said one inductive element, and means for tuning said two resonant circuits including a tuning core movable within said one inductive element along the axis common to both of said inductive elements to simultaneously and uniformly vary the mutual inductance of said coils and the reactance of said other coil to provide for the application of a substantially uniform voltage on the grid of said vacuum tube.
2. In a tuning system having a capacitive element and a vacuum tube with a control grid, the combination of a pair of inductive elements of substantially the same length serially aiding connected and concentrically arranged with one inductive element inserted entirely within the other but spaced therefrom radially, said inductive elements having a mutual inductance and being connected with said capacitive element to form a parallel resonant circuit, with the voltage developed across said other inductive element being applied on said control grid, and a series resonant circuit including said capacitive element and said one inductive element, and means for tuning said two resonant circuits including a tuning core axially movable within said one inductive element and uniformly varying the mutual inductance of said two inductive elements to provide for the application of a uniform response gain on said control grid.
3. In a tuning system including a capacitive element and a pair of vacuum tubes each of which has a control grid and a plate, the combination of a pair of mutually coupled inductive elements of substantially equal length, means for mounting said elements so that they are concentrically arranged in a spaced relation with one inductive element entirely within the other lengthwise thereof and having a junction therebetween, a parallel resonant circuit including said capacitive element and said pair of inductive elements, a series resonant circuit including said one inductive element and capacitive element, with said two resonant circuits being resonant at different frequencies, the control grid of one of said tubes and the plate of the other tube being connected to said coil junction, with the voltage applied on the grid of said one tube being the voltage developed by said other inductive element, and means for tuning said two circuits including a tuning element movable within said inductive elements along their common axis and concurrently varying the inductance of each of said inductive elements and the reactance of said other inductive element at a uniform but different rate to effect a proper tracking between the

resonant frequencies of said two circuits and provide a high image attenuation with a uniform response gain over a wide frequency range.

4. In a tuning system including a capacitive element and a pair of vacuum tubes each having a control grid and a plate, the combination of a pair of inductive elements of substantially equal length serially aiding connected and concentrically arranged in a spaced relation with one thereof inserted entirely within the other lengthwise thereof, a parallel resonant circuit including said capacitive element and said pair of inductive elements, a series resonant circuit including said capacitive element, said one inductive element and a junction therebetween, with the inductance of said other inductive element being applied on the grid of one of said vacuum tubes, and the plate of said other vacuum tube being connected to said junction, and means for tuning said two resonant circuits including a tuning core axially movable within said one inductive element to uniformly and simultaneously vary the inductance of said two coils over their length to provide for a substantially uniform response gain being applied on the grid of said one tube.

5. A tuning system for a radio receiver having a pair of inductive elements serially aiding connected and concentrically arranged in a spaced relation with one thereof within the other, a parallel resonant circuit including said pair of inductive elements and a capacitive element connected in series therebetween, a series resonant circuit including said capacitive element and said one inductive element, and means for tuning said

two resonant circuits including a magnetic core movable within said one inductive element and axially relative to the other inductive element to simultaneously vary the reactance of said other inductive element and the inductance of said two inductive elements over their complete lengths, with the reactance of said other inductive element and the mutual inductance between said two inductive elements providing for a substantially uniform response gain with high selectivity.

6. In a tuning system having a tuning circuit including a capacitive element and a vacuum tube with a control grid, the combination of a pair of inductive elements of substantially the same length serially aiding connected and concentrically arranged with one inductive element inserted entirely within the other but spaced therefrom radially, said inductive elements having a mutual inductance, and said one inductive element and said capacitive element being connected together in series across said other inductive element, with said control grid being connected in said circuit so as to have at least the voltage developed by said other coil applied thereon, and means for tuning said circuit including a tuning core movable within said one inductive element along the axis common to both of said inductive elements to simultaneously and uniformly vary the mutual inductance of said coils and the reactance of said other coil to provide for the application of a substantially uniform voltage gain on the control grid of said vacuum tube.

RINALDO DE COLA.
